UNITED STATES PATENT OFFICE.

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY.

JAVELIN.

Application filed June 24, 1925. Serial No. 39,261.

To all whom it may concern:

Be it known that I, WILLIAM F. REACH, a citizen of the United States, and resident of Springfield, in the county of Hampden and State of Massachusetts, have invented certain new and useful Improvements in Javelins, of which the following is a specification.

The rules governing the throwing of the 10 javelin limit the length, weight and point of balance thereof.

The minimum weight allowed, which of course is that desired by competitors, forces the use of a very slender shaft. The 15 accepted and, so far as I am aware, the only method of javelin construction, has been the provision of a steel point of approximately sixteen inches in length into which has been inserted and secured the end of an ash or 20 birch shaft.

The total length of the javelin is approximately eight feet, six inches, and the wood shaft is necessarily relatively long and very slender.

25 Such construction has resulted in frequent breakage of the wood shafts due to the excessive whip which takes place as the point or head penetrates the ground, which breakage it has thus far been impossible to avoid.

30 My present invention aims to provide a javelin in which this tendency to breakage will be eliminated and the invention includes the novel construction hereinafter described and defined by the appended claims.

35 A javelin constructed in accordance with my invention is illustrated in the accompanying drawing, in which:—

The figure shows the same in elevation, partly in section and partly broken away.

40 In this drawing the metal head is indicated at 1, comprising a pointed end 1^a and a body of light gauge tubing into which the end of the shaft 2 is inserted and suitably secured.

45 In all javelins the point of balance is considerably forward of the center, that is, of a point midway between the ends, and it is between this point of balance and the head, and usually closely adjacent the head, that 50 the breakage occurs. Such a point of balance is indicated by the dotted line x—x.

In my improved construction, I make the head of such length that it is not less than one-third the total length of the javelin, this 55 being the minimum length of the point

whereby there is a noticeable lessening in the vibration of the shaft.

The tubing of the head is made of such gauge or thickness that the normal and required balance is preserved. The usual hand grip winding is indicated at 3.

The construction above described not only produces a javelin which is free from liability of breakage as above described, but one which can be thrown to a greater distance, as has been demonstrated by actual use.

The official rules specify that a javelin shall be at least 8', 6 3/8" in length, not less than 1.76 pounds in weight, and the center 70 of gravity not less than 2.953 feet, nor more than 1.203 yards from the point, and a javelin constructed according to this invention conforms to the above official specifications.

It is desirable that the forward end of 75 the wood shaft shall extend substantially the full length of the tubing and abut against the closed end or point thereof.

I find that by providing the shaft within the tubing with elongated annular reduced 80 portions indicated at 2^a and 2^b, I secure a reduction in weight, and this, by its three point contact, facilitates the insertion and securing of the shaft in the tubing in a tightly fitting manner.

Having thus described my invention, what I claim is:—

1. A javelin having a metallic head and a wooden shaft, the head being of a length not less than one-third the length of the shaft, 90 the center of gravity of the javelin being not less than 2.953 feet nor more than 1.203 yards from the point thereof.

2. A javelin having a metallic tubular head and a wooden shaft, the head being of 95 a length not less than one-third the length of the shaft, the portion of the shaft within the head having an elongated annular reduced portion providing spaced contact portions engaging the inner wall of the head.

3. A javelin having a metallic tubular head and a wooden shaft, the head being of a length not less than one-third the length of the shaft, the portion of the shaft within the head having a pair of annular elongated reduced portions giving a three point contact between the shaft and inner wall of the head.

In testimony whereof, I affix my signature.
WILLIAM F. REACH.
